UNITED STATES PATENT OFFICE

2,520,377

SWING SEAT

Benton Schrougham, Beech Grove, Ind.

Application July 3, 1948, Serial No. 36,911

7 Claims. (Cl. 155—58)

1

The object of the present invention is to provide a swing seat which shall be extremely simple in construction and inexpensive to manufacture, and which comprises a seat section and a back section hingedly associated with each other and adapted to assume any one of a plurality of relative positions. A further object of the invention is to provide improved means for retaining the seat section and back section in selected relative positions. A further object of the invention is to provide, in an organization of the character described, suspension means for the chair or seat of such character that force exerted upon the respective sections of the chair by the suspension means shall be of such character as to tend to render more secure the connection between the frames or sections, whereby disengagement of that connection, and accidental relative movement between the sections, during use of the chair, is positively prevented.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not exceeded.

Fig. 1 is a perspective view of the chair of the present invention suspended with its respective parts in one position of adjustment;

Fig. 2 is a similar view showing a different position of adjustment of the parts;

Fig. 3 is an enlarged perspective view showing a detail; and

Fig. 4 is a reduced perspective view including an illustration of suspension means for the chair.

Referring more particularly to the drawings, it will be seen that my chair comprises a generally U-shaped seat frame 10 comprising a curved base 11 and substantially parallel legs 12 and 13; and a generally U-shaped back frame 14 comprising a curved base 15 and substantially parallel legs 16 and 17. A web 18 is formed to provide a plurality of perimetral, tubular pockets 19 and adapted to be threaded onto the legs 12 and 13, and a pocket 19' adapted to be closed about the curved base 11 after the pockets 19 have been positioned on the legs; and with other pockets 20 adapted to be threaded on the legs 16 and 17 and an end pocket 20' adapted to be closed about the curved base 15 of the back section 14.

Pivot means 21 and 22, which may be bolts,

rivets, or other suitable elements, pivotally connect the extremities of the legs 16 and 17 of the back frame 14 with the extremities of the corresponding legs 12 and 13 of the seat section 10 to permit hinged action between the two frames 10 and 14.

10 A rigid arm rest 23 is pivotally associated with the back frame leg 16 at a point intermediate the ends of said leg, and curved as shown to terminate in a flattened portion 25. A bolt, rivet, or other suitable pivot element 24 mounts said arm rest 23 on the leg 16.

15 The leg 12 of the seat frame 10 is formed, at spaced points in its length, with a plurality of upwardly opening slots, two of such slots, 26 and 27, being shown in the illustrated embodiment of the invention.

20 A similar arm rest 28 is pivotally mounted as at 29 upon the back frame leg 17, and is flattened as at 30 at its free end. The leg 13 of the seat frame is provided, at points in its length corresponding to the location of the slots 26 and 27, with similar, upwardly opening slots 31 and 32. It will be clear from an examination of the drawings forming a part hereof that the flattened portions 25 and 30 of the arm rests 23 and 28 are selectively receivable in the slots 26 or 27 and 31 or 32 of the seat frame legs 12 and 13; and that, so long as said flattened portions are retained in selected slots, a predetermined angular relation between the seat frame 10 and the back frame 14 will be maintained.

25 A flexible element 33 has one end secured at 34 to the leg 16 of the back frame member near the curved base 15 thereof, and its other end secured to the leg 12 of the seat frame 10 at a point 35 near the base 11 thereof. A second flexible element 36 has its ends connected, at 37 and 38 to corresponding points on the back frame leg 17 and the seat frame leg 13. For a reason which will appear, I presently believe that the flexible elements 33 and 36 will most advantageously be link chains.

30 A suspension element 39 is adapted to be connected to the chain 33, at a point 40 (Fig. 1) and a companion suspension element 41 is adapted to be connected to the element 36 as at point 42. The suspension elements 39 and 41 may desirably be supported upon a standard swing frame, for instance, of the character illustrated at 43 in Fig. 4.

35 It will be obvious, upon an inspection of the drawings, that the arrangement of parts is such that the suspensory force exerted, by the suspension elements 39 and 41, upon the flexible ele-

ments 33 and 36, tends to swing the frames 10 and 14 relatively toward each other about the pivot points 21 and 22.

With the frames 10 and 14 in the positions illustrated in Fig. 1 the flattened ends 25 and 30 of the rigid arm rests 23 and 28 register with, and are receivable in, the slots 26 and 31, respectively. The depth of penetration of said arm rest ends into the slots may be limited either by the flaring enlargement of said arm rest ends or by engagement of the extremities of said flattened portions with the inner surfaces of the legs. The important point, however, is the fact that the forces applied to the frames 10 and 14, through the elements 33 and 36, by the elements 39 and 41, tend to increase the depth of penetration of said arm rest ends into the associated slots; and the greater will be the weight supported in the chair, the greater will be the effective force tending to prevent accidental withdrawal of said arm rest ends from the associated slots, thereby guarding against accidental changes in the relative positions of the frames 10 and 14.

Preferably, but not necessarily, the frames 10 and 14 and the arm rests 23 and 28 will be formed of standard tubular stock.

It is desired to swing a baby, or if, for any other reason, the occupant of the illustrated chair chooses to recline, the relative adjustment of the parts may be shifted from that illustrated in Fig. 1 to that illustrated in Fig. 2, the arm rest ends 25 and 30 being removed from the slots 26 and 31 and engaged in the slots 27 and 32. At the same time, the suspension elements 39 and 41 will be disconnected from the points 40 and 42 on the flexible elements 33 and 36 and reconnected to said elements at the points 40' and 42'. Because of the desirability of readily shifting the points of connection of the elements 39 and 41 with the elements 33 and 36, the use of chains to connect the two frames 10 and 14 is highly desirable, since, the suspension elements 39 and 41 being provided at their lower ends with suitable attaching means, such as hooks, snap hooks, split rings, or the like, said elements may be readily disconnected from any link of each of the chains 33 and 36 and reconnected to said chains at any other links in their lengths.

I claim as my invention:

1. A suspended chair comprising a seat frame and a back frame, the lower portion of the back frame and the rear portion of the seat frame being pivotally associated, flexible means connecting the upper portion of the back frame with the forward portion of the seat frame, suspension means connected with said flexible means to support said chair through said flexible means and to exert thereon a force tending to move the points of said frames connected by said flexible means toward each other, and rigid means pivotally associated with one of said frames and having a post-and-socket association with the other of said frames to resist such tendency.

2. The chair of claim 1 in which said other frame is provided with a slot enterable by said rigid means upon movement of said points toward each other, whereby said force exerted by said suspension means tends to seat said rigid means firmly in said slot.

3. The chair of claim 2 in which said other frame is provided with a plurality of slots differently spaced from the region of pivotal connection of said frames, and selectively enterable by said rigid means.

4. The chair of claim 2 in which said slot opens through the upper surface of said seat frame and said rigid means comprises a curved arm rest pivoted at one end to said back frame and reduced in lateral width adjacent its opposite end to enter said slot.

5. The chair of claim 1 in which said flexible means comprises a chain and in which said suspension means is selectively connectible to said chain at any one of a plurality of points in the length of said chain.

6. A suspended chair comprising a U-shaped seat frame and a U-shaped back frame, means providing a pivotal connection between the ends of the legs of said respective frames, a chain connected to each leg of said back frame near the curved base thereof and to the corresponding leg of said seat frame near the curved base thereof, suspension means selectively attachable to each of said chains at any one of a plurality of points in the length of said chain, each leg of said seat frame being provided, in the region between said pivotal connection and the point of connection of a chain thereto, with a plurality of upwardly-opening slots differently spaced from said pivotal connection, and a rigid arm rest pivotally connected to each leg of said back frame in the region between said pivotal connection and the point of connection of a chain thereto, the free end of each arm rest being selectively enterable in the slots of the corresponding leg of said seat frame.

7. The chair of claim 6 in which said frames and said arm rests are formed of tube stock and the terminal portions of the free ends of said arm rests are laterally flattened for reception in said slots.
